LEFT TURN SIGNAL SYSTEM

Christopher B. Green, Denton, Nebr.

Application March 20, 1935, Serial No. 12,024

2 Claims. (Cl. 116—52)

My invention relates to signals and more particularly to signals of the type used on automobiles to indicate an intention to turn, the primary object of the invention being to provide a signal which will not detract from the appearance of the car and which is of the simplest possible construction.

Another object of the invention is the provision of a signal adapted to be secured to the car door and arranged so that it will fold into the space between the inner panel and outer wall of the car door to be entirely concealed.

Another object of the invention is the provision of a signal which can be actuated to either operative or inoperative position by a single flick of the hand.

Another object which I have in view is the provision of a signal in combination with a clip which releasably holds the signal in either its operative or its inoperative position.

Another object of the invention is the provision of a signal arm of very thin metal construction so that it will pass readily through a narrow slot in the outer wall of the car door, the signal being provided with a plate to entirely conceal the slot when the signal is in its inoperative position.

Having in view these objects and others which will be pointed out in the following description, I will now refer to the drawing, in which

Figure 1 is a view in cross section of the car door showing the signal in its operative position.

Figure 2 is a view similar to Figure 1 but showing the signal in its inoperative position.

Figure 3 is a view in perspective of the signal member.

Figure 4 is a perspective view showing the attaching means for the pin which serves as a pivot for the signal member.

Figure 5 is a view looking toward the inner side of the inner panel of the car door and showing particularly the spring clip.

Figure 6 is a sectional view of the inner panel of the car door and also showing the spring clip.

Figure 7 is a view in side elevation of a portion of the car with my signal secured thereto.

As shown in Figure 3 the device includes a signal plate 10 terminating at its inner end in a hook-like member 11 which is formed by cutting an arcuate slot in the plate. A lever arm 12 projects from the lower edge of the signal plate 10 and this lever arm terminates in a handle 13. The signal plate 10 and the lever arm 12 are further connected by a brace 14. The parts 10, 11, 12, 13 and 14 are integral and they may be

struck out of a single sheet of metal. For convenience the handle 13 may be rounded. The plate 15 is secured to the signal plate 10 at its upper edge and transversely thereto so that the end elevation or transverse section of the parts 10 and 15 will be T-shaped in outline.

As shown in Figures 1 and 2 the signal plate 10 is mounted to swing about a pin 16 which is secured to the outer wall of the car door, the securing means being shown in Figure 4. The car door is provided with a very narrow slit to permit the passage of the signal plate 10, and the pin 16 is positioned across the slit and spaced inwardly therefrom. Two brackets 17 are therefore secured to the outer wall of the car door so as to project slightly into the space within the car door. Because of the arcuate slot in the signal plate 10 it is an easy matter to engage the signal plate 10 with the pin 16 as shown in Figures 1 and 2. When the signal is in its inoperative position as shown in Figure 2 the plate 15 covers and conceals the slit and prevents the entrance of water and dust or other foreign matter.

The inner panel of the car door is provided with a slot for the movement of the lever arm 12. Adjacent the slot of the inner panel of the car door is a clip 18 as shown in Figures 5 and 6. This clip is preferably formed from resilient metal which is twisted into two half turns with projections or bends 19 extending part way across the slot as shown in Figure 5. As shown in full lines in that figure the lever arm 12 is in its lowermost position with the signal in its operative position. The lever arm 12 is yieldably held in its lowermost position by the lower of the two bends 19. A slight push upwardly of the handle 13 will cause the lever arm 12 to ride over the lower bend 19 and then over the upper bend 19 to its dotted line position in Figure 5 in which the signal will be in its inoperative position as shown in Figure 2. The clip 18 is highly resilient and the bends 19 will readily yield for the passage of the lever arm 12 but they will not yield in response to the vibrations of the car during driving.

One of the suggested installations is shown in Figure 7. It is generally advisable to select the most convenient position relative to the driver's hand on the steering wheel. A momentary flick from the driver's hand is all that is necessary to move the signal from either position to the other and it is only for a moment that the driver releases his left hand from the steering wheel. It is necessary, however, to select such a position as not to interfere with the sliding windows.

- of the car nor with the door lock or latch. The installation thus necessarily depends to some extent on the car construction but the arrangement which I show in my drawing is adapted for installation in practically every type of closed car. It is also contemplated to match the color of the plate 15 with that of the car body so that the signal in its inoperative position will be inconspicuous and almost invisible.
- 10 Having thus described my invention in such full, clear, and exact terms that its construction and operation will be readily understood by others skilled in the art to which it pertains, what I claim as new and desire to secure by Letters Patent of the United States is:
- 15 1. In combination, an automobile door having spaced apart inner and outer walls each provided with a vertical slot, a pivot pin secured to said outer wall and spaced inwardly therefrom 20 and transversely of the slot thereof, a signal arm having an open ended arcuate slot at its inner or upper extremity for releasably engaging said pivot pin, an arcuate lever projecting from said signal arm and through the slot of said inner wall, and a spring clip secured to said inner wall 25 inside said automobile door, said spring clip hav-

ing a pair of stops defining the operative and inoperative positions of said signal arm.

2. In combination, an automobile door having spaced apart inner and outer walls with a hollow space therebetween, said walls being each provided with a vertical slot, a signal arm having a width materially less than the distance between said outer and inner walls, a pivot pin secured to said outer wall and spaced inwardly therefrom adjacent the upper extremity of the 10 slot of said outer wall, said signal arm being provided with an open ended arcuate slot at its inner or upper extremity for releasable engagement with said pivot pin, a transversely positioned plate on said signal arm, said plate having substantially the dimensions of the slot of said outer wall whereby said plate will be continuous with said outer wall when said signal arm is in inoperative position, an arcuate lever projecting from said signal arm and through the 20 slot of said inner wall, and a spring clip secured to said inner wall at the inner side thereof, said spring clip having a pair of stops for defining the operative and inoperative positions of said signal arm. 25
